BARREL

Gunnar Lindwall, Oslo, Norway

Application February 7, 1951, Serial No. 209,722

5 Claims. (Cl. 217—78)

1

The invention relates to an improvement in barrels for the transportation and storage of liquid and solid materials, and it relates more particularly to improved means for securing the heads of barrels in position and in liquid-tight relation to the barrel walls.

According to the present invention, the barrel wall, which may consist of a hollow, cylindrical shell formed of plywood, compressed fiber, laminated, impregnated paper and the like, has hoops mounted inside its opposite ends to support the heads of the barrel. The heads may consist of discs formed of material similar to that of the shell having tapered peripheries for cooperation with retaining hoops of wedges shaped cross-section, mounted outside the heads. The confronting inclined edges of the disc and hoop are generally complementary and may be brought into tight sealing relation by forcing the hoop against the barrel wall and the edge of the disc. Suitable sealing or packing material such as, cotton, wool, impregnated paper, string or the like may be mounted in grooves in the retaining hoop and/or the edge of the disc to insure a liquid-tight seal.

The retaining hoops are split and have wedging surfaces on their free ends so that the hoops can be expanded into tight engagement with the inner walls of the barrels. The wedging action can be obtained with an expander for the hoops or by means of a separate wedge driven between the ends of the hoops. In either case, the ends of the hoops and the wedging means are secured to the wall of the barrel by means of suitable retaining clips, nails, studs or the like to prevent inadvertent detachment of the hoops and heads of the barrel.

The hoops may also be attached to the barrel shell by means of pins, nails, studs or the like.

A reinforcing hoop formed of plywood or the like may be mounted on the exterior of the barrel adjacent each end. These hoops extend from the outer edge of the wall practically to the inner end of the supporting hoop. The reinforcing hoop may be protected and stiffened by means of a metal hoop. To facilitate the attachment of this metal hoop, the reinforcing hoop may be slightly conical or tapered.

For a better understanding of the invention reference may be had to the accompanying drawing, illustrating an embodiment of the invention, in which:

Fig. 1 is a fragmental section through a part of the barrel wall and an adjoining part of a disc;

Fig. 2 is a similar fragmental section through the center part of the barrel wall;

2

Fig. 3 is a view in front elevation of a clip to attach the retaining hoop to the barrel shell;

Fig. 4 is an end view of the clip of Fig. 3;

Fig. 5 is a view in section through the barrel wall and the ends of the retaining hoop taken on a plane perpendicular to the ends of the barrel, and

Fig. 6 is a view in section through the wall, hoop and head of the barrel showing a modified type of seal therefor.

The barrel illustrated in Fig. 1 of the drawings includes a cylindrical shell 10 formed of plywood. The shell has heads 11 at its opposite ends, these heads being formed of plywood or other suitable material. Each head 11 is supported in the shell by means of an internally mounted hoop 12 of plywood which is spaced from the end of the shell 10. The inner edge of the hoop 12 may be tapered as at 13 to facilitate the emptying of the barrel.

Each end of the barrel shell 10 may be reinforced with a suitable exterior reinforcing hoop 14 which extends from the end of the shell to about the outer edge of the supporting hoop 12. The barrel shell may be reinforced further by means of a metal hoop 15 which is forced over the hoop 14 and secured thereto by punched in tongues 16 on the hoop 15. The hoop 14 may be tapered toward the end of the shell to facilitate the application of the hoop 15 to it.

The disc or head 11 at each end of the barrel has a bevelled or inclined surface 17 at its outer edge for cooperation with a complementary inclined surface 18 on a retaining hoop 19. The hoop 19 has a generally wedge shaped lower cross-section which enables it to be wedged tightly between the surface 17 of the head 11 and the inner wall of the shell 10. A liquid-tight seal may be obtained between the surfaces 17 and 18 by inserting a sealing or caulking composition, such as impregnated cotton, wool or paper cord, in a groove 20 in the inclined surface 17 of the head 11, this composition being compressed by the wedging action of the hoop 19. Also the outer surface of the hoop 19 or the inner surface of the shell 10 may have a groove 21 in it to receive a sealing cord or the like to prevent leakage between the shell 10 and the outer surface of the hoop 19.

As shown in Fig. 6, sealing of the barrel may be accomplished by providing the outer surface of the hoop 19a for the barrel with a groove 21a to receive a sealing cord or packing 21b for cooperation with the shell 10a.

As shown in Fig. 1 the hoop 19 may be split 55 as at 22 to provide opposed free ends 23 and 24.

These ends are slightly tapered so that they converge downwardly. The hoop 19 is of less outer circumference than the inner circumference of the shell so that the hoop can be inserted into and removed from the shell easily.

When the hoop is inserted into the end of the shell 10 to secure the head 11 in position, the ends of the hoop 19 are forced apart and a tapered wedge 25 is inserted between the free ends 23 and 24. The wedge is driven inwardly to expand the hoop 19 into tight engagement with the inner wall of the shell and the hoop is further driven into the shell so that its surface 18 is in tight engagement with the surface 17 of the head 11. The lower edge of the wedge 25 may also be tapered and provided with a groove in its outer surface to receive a caulking or sealing compound, as described above. When the hoop 19 is sealed tightly against the barrel shell 10 and the head 11, the hoop is secured in position by means of nails 26, wires, pins or the like extending through the hoop 19, the shell 10 and the reinforcing hoop 14. The wedge 25 may be fixed in position by means of a clip 27 having a flat plate 28 to engage the inner surface of the wedge, and a bent over flange 29 to engage the end of the wedge and the end of the shell 10. The flange 29 carries teeth 30 which may be driven into the end edge of the shell 10. A nail 26 is then driven through the hole 31 in the plate 28, into the hoop 19 and the shell 10 to secure the clip 27 and wedge 25 in position.

The clips 27 may also be used at other points around the barrel to secure the hoop 19 in position.

The head 11 of the barrel can easily be removed by pulling out the fasteners 26, prying up the clips 27 and knocking out the wedge 25. This releases the hoop 19 and the head 11.

The construction of the hoop 19 can be varied somewhat. For example, as shown in Fig. 5, the ends of the hoop 19, may be tapered lengthwise and overlapped. This hoop should be about the same in circumference as the inner circumference of the shell. It can be expanded against the wall of the shell 10' by sliding its inclined ends on their inclined surfaces. The ends of the expanded hoop are then secured in overlapping position by means of a clip 27' like the clip 27, described above.

To enable the barrel to be rolled easily, a hoop 33 of plywood or the like may be secured to the outside of the barrel at about its mid-portion as shown in Fig. 2. The hoop 33 should be thicker than the combined thicknesses of the hoops 14 and 15.

The above described barrel constructions are strong and liquid-tight and can be assembled, disassembled and reassembled without difficulty. They are light in weight and can be handled easily. Inasmuch as the barrels are adequately reinforced at their ends and the heads are wedged and secured in position at the reinforced portions of the barrel, the heads are not easily dislodged even when the barrels are handled roughly.

It will be understood that the barrels may be varied in shape and size and that they may be constructed of materials other than plywood, if desired. Therefore, the barrels chosen for purposes of description should be considered as illus-

trative and not as limiting the scope of the following claims.

I claim:

5 1. A container for liquids and solids comprising a substantially cylindrical hollow shell, a closure for each of the ends of said shell, one of said closures including a disc-like head having a peripheral surface including a cylindrical edge portion and an acutely beveled peripheral edge and a groove in said edge, packing material in said groove, a shoulder in said shell to support said head against inward movement with said beveled edge facing outwardly and the cylindrical edge portion adjacent to said shoulder, a split hoop on the opposite side of said head from said supporting hoop, said hoop having an inner edge portion of wedge shaped cross section fitting between the shell and the beveled edge of said head in wedging engagement therewith and in sealing engagement with the packing material in said groove, and means to expand said split hoop to force it tightly against the interior of said shell to anchor said head against movement out of said shell.

20 2. A container for liquids and solids comprising a substantially cylindrical hollow shell, a shoulder member inside said shell adjacent one end, a disc-like head supported against inward movement by said shoulder, said head having a peripheral surface including a cylindrical edge portion and an acutely beveled edge, a split hoop on the opposite side of said head from said shoulder, said hoop having opposed free ends and a beveled edge complementary to the beveled edge on said head and engageable therewith to wedge said hoop between said head and said shell, one of said beveled edges having a groove therein, packing material in said groove and engaging the other beveled edge to effect a seal therewith, and wedge means at said free ends of said split hoop to expand said hoop into engagement with said shell.

25 3. The container set forth in claim 2 in which the inner surface of said shell has a circumferential groove opposing said split hoop, and a sealing material in said groove to seal said hoop to said shell.

40 4. The container set forth in claim 2 in which said split hoop has a circumferential groove in its exterior surface, and a sealing material in said groove to seal said hoop to said shell.

45 5. The container set forth in claim 2 in which the ends of said split hoop converge inwardly, and the wedging means comprises a tapered wedge engaging said ends to expand said hoop.
